9123

UNITED STATES PATENT OFFICE.

LOUISE TULLY, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 14,894, dated March 18, 1884.

Application filed February 13, 1884. Term of patent 3½ years.

To all whom it may concern:

Be it known that I, LOUISE TULLY, of the city, county, and State of New York, have invented and produced a new and original Design for a Pattern of a Lady's Costume, (numbered 9,123;) and I do hereby declare that the engraved prints accompanying this specification convey to any one accustomed to using paper patterns a clear understanding of how a garment made up by the pattern will appear.

The design shows a round walking-skirt and an overdress. The skirt displays a long narrow panel upon the center of its front. The overdress exhibits a closely-fitting basque-body, which displays at the sides oval paniers that round away from the upper front corners

and show draping plaits in their back edges, and at the back a full deep drapery that shows shirrings and loopings at the center, and draping plaits in its front edges, a standing collar, and coat-sleeves exhibiting their lower parts reversed in cuffs.

What I claim as my invention, and desire to secure by Letters Patent, is—

The design for a lady's costume, as shown in the engraved prints accompanying this specification.

LOUISE TULLY.
